UNITED STATES PATENT OFFICE.

DAVID FITCH ROBBINS, OF BERLIN, MINNESOTA.

DRAFT-EQUALIZER.

SPECIFICATION forming part of Letters Patent No. 283,086, dated February 5, 1884.

Application filed December 5, 1883. (No model.)

To all whom it may concern:

Be it known that I, DAVID FITCH ROBBINS, of Berlin, Steele county, and State of Minnesota, have invented a new and useful Improvement 5 in Four-Horse Eveners, of which the following is a full, clear, and exact description.

Reference is to be had to the accompanying drawings, forming a part of this specification, 10 in which similar letters of reference indicate corresponding parts in all the figures.

Figure 1 is a plan view of my improvement. Fig. 2 is a sectional front elevation of the same, taken through the line *xx*, Fig. 1. Fig. 15 3 is sectional front elevation of the same, taken through the line *yy*, Fig. 1.

The object of this invention is to provide means for attaching four horses abreast to a harvester in such a manner that each horse 20 will be compelled to draw one-quarter of the load.

The invention consists in a four-horse evener constructed with a cross-bar attached to the tongue, and having pulleys at its ends, around 25 which passes a chain connected at its ends with levers pivoted at their inner ends to the tongue, and provided at their outer ends the one with a whiffletree and the other with an ordinary three-horse evener, so that the draft 30 will be equally divided. The lever that carries the three-horse evener is strengthened against the downward pull of the said evener by a brace attached to the outer part of the said lever, and pivoted to the tongue by the 35 pivoting-bolt of the said lever, as will be hereinafter fully described.

A represents the tongue of a harvester.

To the rear part of the tongue *A* is attached the center of a cross-bar, *B*, which is strengthened 40 in position by a curved brace, *C*, formed upon or attached to the said cross-bar, and attached at its center to the tongue *A*. The ends of the cross-bar *B* are bent upward and inward into bow form, and to them are pivoted grooved pulleys *D*, around which passes 45 a chain, *E*, the bends of the end bows of the cross-bar *B* serving as guards to keep the said chain in place upon the said pulleys. One end of the chain *E* is connected by a clevis, *F*, 50 or other suitable means, with a lever, *G*, at

a point midway between the center and the pivot at the inner end of the said lever. The inner end of the lever *G* is pivoted to the tongue *A* by a bolt, *H*, and with its outer end is connected a whiffletree, *I*. The other end 55 of the chain *E* is connected by a clevis, *J*, or other suitable means, with the center of the lever *K*, the said lever *K* being made of such a length that the point of attachment of the end of the chain *E* to the said lever *K* will be 60 at a distance from the central line of the tongue *A* equal to three times the distance of the point of attachment of the first-mentioned end of the said chain *E* to the lever *G* from the said central line of the tongue *A*. The inner 65 end of the lever *K* is pivoted to the tongue *A* by a bolt, *L*, and with its outer end is connected an ordinary three-horse evener, *M N O*. With this construction one horse will work at one side of the tongue *A* and three 70 horses at the other side of the said tongue, and each horse will be compelled to draw one-quarter of the load.

To the lower side of the tongue *A* is pivoted, by the bolt *L*, that pivots the inner end of the 75 lever *K* to the said tongue, the inner end of the brace *P*, the outer part of which is made with an upward offset, and its outer end is pivoted by a bolt, *Q*, to the lever *K* about midway between the points of attachment of 80 the chain *E*, and the three-horse evener *M N O*, so that the said lever *K* will be strengthened against the downward pull of the weight of the three-horse evener *M N O*, connected with the outer end of the said lever *K*. 85

In the bow of the cross-bar *B*, at the side of the tongue *A* at which the three horses work, are formed two or more holes to receive the pivot of the pulley *D*, so that the said pulley can be adjusted nearer to or farther from the 90 tongue *A*, according as the machine to which the evener is to be attached may have more or less side-draft.

The upper ends of the pivoting-bolts *H L* are strengthened against the pressure of the 95 levers *G K* by a hammer-strap, *R*, hinged at one end to the tongue *A* by a staple, *S*, or other suitable means.

Having thus described my invention, I claim as new and desire to secure by Letters Patent— 100

1. A four-horse evener constructed substantially as herein shown and described, and consisting of the cross-bar B, having grooved pulleys D, the chain E, passing around the said pulleys, and the levers G K, connected with the ends of the said chain, and provided the one with a whiffletree and the other with a three-horse evener, as set forth.

2. The combination, with the tongue A, the whiffletree I, and the three-horse evener M N O, of the cross-bar B, the pulleys D, the chain E, and the levers G K, substantially as herein shown and described, whereby the draft will be equally divided, as set forth.

3. In a four-horse evener, the combination, 15 with the tongue A and the lever K, of the brace P, substantially as herein shown and described, whereby the said lever is strengthened against the weight of the three-horse evener connected with its outer end, as set forth.

DAVID FITCH ROBBINS.
